UNITED STATES PATENT OFFICE

130,634

DESIGN FOR A BADGE OR SIMILAR ARTICLE

Alma Brouse, Denver, Colo.

Application July 15, 1941, Serial No. 102,155

Term of patent 3½ years

To all whom it may concern:

Be it known that I, Alma Brouse, a citizen of the United States, residing at Denver, in the county of Denver and State of Colorado, have invented a new, original, and ornamental Design for a Badge or Similar Article, of which the following is a specification, reference being had to the accompanying drawing, forming part thereof.

In the drawing:

Fig. 1 is a front view of badge or similar article illustrating the design.

Fig. 2 is a side edge view thereof.

I claim:

The ornamental design for a badge or similar article, as shown.

ALMA BROUSE.
